(57) **CLAIM**

The ornamental design for a vehicle wheel chock face plate,
as shown and described.

DESCRIPTION

FIG. 1 is a front perspective view of a vehicle wheel chock
face plate of our new design.

FIG. 2 is a rear perspective view of the vehicle wheel chock
face plate of FIG. 1.

FIG. 3 is a rear view of the vehicle wheel chock face plate of
FIG. 1.

FIG. 4 is a front view of the vehicle wheel chock face plate of
FIG. 1.

FIG. 5 is a top view of the vehicle wheel chock face plate of
FIG. 1.

FIG. 6 is a bottom view of the vehicle wheel chock face plate
of FIG. 1.

FIG. 7 is a left side view of the vehicle wheel chock face plate
of FIG. 1, the right side view being a mirror image thereof.

FIG. 8 is a front perspective view of a second embodiment of
vehicle wheel chock face plate of our new design.

FIG. 9 is a rear perspective view of the vehicle wheel chock
face plate of FIG. 8.

FIG. 10 is a rear view of the vehicle wheel chock face plate of
FIG. 8.

FIG. 11 is a front view of the vehicle wheel chock face plate of
FIG. 8.

FIG. 12 is a top view of the vehicle wheel chock face plate of
FIG. 8.

FIG. 13 is a bottom view of the vehicle wheel chock face plate
of FIG. 8; and,

FIG. 14 is a left side view of the vehicle wheel chock face
plate of FIG. 8, the right side view being a mirror image
thereof.

The broken lines are included for the purpose of illustrating
environment and form no part of the claimed design.
